DEVICE FOR DRESSING PROFILED GRINDING WHEELS

Fernand Turrettini, Bellevue-Geneva, Switzerland, assignor to Societe Genevoise d'Instruments de Physique, Geneva, Switzerland, a firm of Switzerland

Application June 15, 1940, Serial No. 340,811
In Switzerland June 24, 1939

1 Claim. (Cl. 125—11)

The present invention relates to a device for dressing profiled grinding wheels, in particular wheels for grinding screw threads.

Grinding wheels used for this purpose are, generally speaking, constructed in the form of a double cone or two equally shaped truncated cones having their bases opposite each other, whereby an arc of a circle of determined radius whose value depends upon the thread to be ground connects the sides of the two cones.

The known devices employed for dressing wheels of this kind are generally composed of two individually controlled members, a rotatable member for dressing the rounded head of the profile of the wheel, the angle of rotation of this member being determined by the angle between the sides of the thread to be ground, and a member capable of rectilinear or oscillatory motion about an axis perpendicular to the axis of rotation of the rotatable member for dressing the flanks of the said profile. To operate these members, separate controls have to be actuated in a series of subsequent operations necessary for effecting the flank-dressing and the rounding-off of the head of the profile. The result of this arrangement is an inconvenient handling as also a considerable loss of time.

The object of the present invention is to avoid these inconveniences and to provide a device permitting to rapidly and easily effect the different dressing operations on the grinding wheel. More specially the invention resides in the provision of an unique driving organ which controls the different movements of the dressing tool and which by reason of a sole continuous displacement causes the said tool to describe its complete path composed of two straight lines connected to each other by an arc of a circle.

In order that this invention may be clearly understood and readily carried into practice reference may be had to the appended explanatory drawings showing, by way of example, a preferred embodiment of the invention.

Fig. 1 is a general sectional view of the whole device according to the invention.

Fig. 2 is a top plan view of said device.

Fig. 3 is a sectional view taken on the line III—III in Fig. 1, illustrating a detail.

Figs. 4 and 5 are examples of profiles of the grinding wheel, illustrating the operation of the device.

The represented trueing device comprises a slide 2 carried by a body member 13 and being displaceable forward and backward along a guide 3 of said member. An arm 2a is solidal with the

said slide and extends upwardly therefrom, terminating at its free end in a holder 2b for a trueing diamond 1 intended to dress the profile of the grinding wheel W. The diamond is suitably supported in the holder 2b and can be easily and accurately adjusted therein with respect to the grinding wheel W so as to assume an initial working position and to be gradually advanced from this position for the subsequent dressing of said wheel. 5 designates a relatively short rack fixed to the inside of the slide 2 and meshing with a pinion 4 of a movement transmitting device which will be described later.

The body member 13 is fixedly mounted on a second body member 14 which affords a pivot 20 rotatably supported in the machine bed 27 by means of two vertically spaced low-friction bearings 21 and 22, such as ball or roller bearings. The body member 14 and pivot 20 are made of one piece and form together with the body member 13 the swivel base of the trueing device.

Between the slide 2 and the swivel base of the device is disposed a coil compression spring 23. As clearly shown in Fig. 3, this spring is lodged in a sheath 6 of the body member 13 and freely embraces a rod 26 extending entirely through said sheath and fixed at both ends to the slide 2. Each extremity of the spring 23 bears upon a ring 23a seated against a shoulder 26a of said rod, the spring being set between the two rings 23a with a certain initial stress so as to assure a rigid connection between the slide 2 and the swivel base 13, 14, 20. Owing to the low-friction bearings 21 and 22 employed for rotatably supporting the said swivel base on the machine bed 27, it is not necessary to provide for an excessively strong spring action; a spring of relatively light stress may be sufficient to assure greatest reliability of service, as will later appear.

As clearly shown in Fig. 1, the body member 13 is drilled transversely across its body for receiving a passing axle 1 the upper end of which carries the pinion 4 meshing with the rack 5 of the slide 2, while the lower end of said axle carries a pinion 8. Also the body member 14 and its pivot 20 are hole bored from end to end to accommodate an axle 10 carrying, on the one side, a pinion 9 meshing with the pinion 8 and, on the other side, a pinion 11 meshing with a pinion 12, the latter being fixed to a hand-wheel or handle not represented. Parts 11, 10, 9, 8, 7 and 4 constitute the movement transmitting device by means of which the slide 2 may be displaced forward and backward on the swivel base 13, 14, 20. In the present instance, the pinions

11 and 12 are shown having helicoidal toothings.

The pivotal movement of the base 13, 14, 20 is regulated by stops 15 and 16 as best seen in Fig. 2. The said stops can be displaced in a sunken circular guideway 28 on the machine bed 27, and they may be temporarily locked in said guideway in any desired position of angular adjustment with respect to the middle plane of the grinding wheel, a series of graduations 17 being provided on the bed 27 adjacent said guideway for determining the exact degree of displacement or angular position of the two stops. 19 designates an abutment piece rigid with the base 13, 14, 20 and adapted to cooperate with the stops 15 and 16 on the machine bed; it carries 15 a pointer 18 sliding on the graduation 17.

The machine bed 27 is also provided with a forked lever 24 which is mounted to revolve upon a short shaft 25 fixed to said bed, and said lever presents two arms 24a and 24b bent inwardly and being adapted to embrace the abutment piece 19 of the swivel base 13, 14, 20 for locking said base in the position shown in the drawings.

The operation of the described device is as follows:

To effect the rounding-off of the head of the wheel profile, the pinion 12 is rotated in clockwise or counterclockwise direction by means of the hand-wheel or handle not represented and thereby transmits its movement through pinion 11, axle 10, pinions 9 and 8, axle 7, and pinion 4 to the rack 5 rigid with the slide 2. The latter is held in position by the coil spring 23 and will not be displaced with respect to the swivel base 13, 14, 20. In consequence, the whole device will rotate on the machine bed 27 about the geometric axis of the pivot 20 until the abutment piece 19 comes to abut against one of the two stops, for instance the stop 15, whereby the diamond 1 follows the arc of a circle a—b the center 40 c of which lies on the geometric axis of the pivot 20 as best seen in Fig. 4.

As soon as the abutment piece 19 abuts the stop 15, the motive power transmitted to the slide 2 through the medium of the above mentioned pinions and axles causes the said slide to be displaced against the action of the spring 23 which is then depressed, thereby allowing the diamond 1 to effect a translatory rectilinear movement tangential to the arc a—b for dressing the right flank b—d shown in Fig. 4. The end d of this tangential stroke will be reached when the spring 23 has been completely depressed.

The pinion 12 is then rotated in the opposite direction whereby the translatory rectilinear movement of the diamond 1 is repeated from b to a, while the spring 23 still presses the abutment piece 19 against the stop 15. When the slide 2 has returned to the normal position wherein the spring 23 retakes its initial tension, the former will again be fast to the swivel base 13, 14, 20 and the diamond 1 will dress the arc of circle in the reverse direction from b to a. Upon reaching the point a, the abutment piece 19 65 comes to abut against the other of said stops 16;

the spring 23 will be again depressed and the pivotal movement of the diamond will be converted in a translatory rectilinear movement for dressing the left flank a—e. It will thus be seen that the operation of the whole device is obtained simply by turning the pinion 12 in clockwise and counter-clockwise direction.

The desired radius of curvature r of the arc of circle a—b may be obtained by adjusting the cutting edge of the diamond 1 at a suitable distance from the geometric axis of the pivot 20; moreover, the aperture angle or working range of the said axis may be determined by the angular adjustment of the stops 15 and 16.

The represented trueing device permits also dressing grinding wheels having a trapezoidal profile as shown in Fig. 5. In this case the wheel is first dressed in the same manner as hereinbefore described to receive a rounded profile as 20 is shown by dotted lines in Figure 5. After this trueing operation is completed, the swivel base 13, 14, 20 is arrested in the middle plane of the grinding wheel by means of the forked lever 24 which is brought into the position shown in the drawings, wherein it clamps the abutment piece 19 of said base between its two arms 24a and 24b. Then the pinion 12 is again rotated while simultaneously applying the diamond 1 against the rounded head of the wheel profile. In this way the said diamond is caused to reciprocate in a rectilinear movement parallel to the axis of rotation of the grinding wheel as indicated by the arrows f in Fig. 5, and at the same time it is advanced towards said axis for the subsequent cutting off of the rounding of the profile.

From the foregoing, it is believed that the construction and advantages of the present invention may be readily understood by those skilled in the art without further description, it being borne in mind that numerous changes may be made in the details disclosed without departing from the spirit of the invention as set out in the following claim.

What is claimed and desired to be secured by Letters Patent is:

In a grinding wheel truing apparatus intended in particular for screw thread grinding machines, in combination, a sliding tool-holder, an inner rack mounted inside the slide of said sliding tool-holder, a base supporting the latter, an inner spring-box mounted in said base and linked with said sliding tool-holder and tending to keep it in neutral position, a pinion engaging said inner rack and mounted on an axle turning freely in said base, reduction gears linking said axle with a driving shaft mounted coaxially in pivot of said base, roller bearings mounted on supporting bed and carrying said pivot, a coaxial semi-circular division traced on said bed, adjustable stops 50 along said division, a fixed lug on said base cooperating directly with said stops, and a retractable intermediate stop and clamp cooperating with said fixed lug to set the base for cylinder truing.

FERNAND TURRETTINI.
